UNITED STATES PATENT OFFICE.

JULIEN STRANDERS, OF NEW YORK, N. Y., ASSIGNOR TO THE UNITED STATES PRINTING & LITHOGRAPH COMPANY, OF NEW YORK, N. Y., A CORPORATION OF OHIO.

DISPLAY DEVICE.

1,098,924.

Specification of Letters Patent.

Patented June 2, 1914.

Application filed May 2, 1913. Serial No. 765,142.

To all whom it may concern:

Be it known that I, JULIEN STRANDERS, a subject of the King of Great Britain, residing in New York, in the borough of Brooklyn, county of Kings, and State of New York, have invented certain new and useful Improvements in Display Devices, of which the following is a specification.

This invention relates to display-devices of that kind which are intended to be set up in show-windows after they have been opened up from their folded or collapsed condition; and for this purpose the invention consists of a display-device comprising a supporting step-shaped rear-member, front-members hinged to the edges of the steps of the rear-member and overlapping each other, and a stay hinged to the center-line of the rear-member and provided with steps for engaging the individual front-members and placing thereby the rear-member and front-members into curved or convex position, as will be fully described hereinafter and finally pointed out in the claims.

In the accompanying drawing, Figure 1 represents a front-view of my improved display-device shown in set-up position for use, Fig. 2 is a vertical transverse section of the same on line 2—2, Fig. 1, Fig. 3 is a vertical transverse section of the display-device, showing it in flat and folded or collapsed condition, and Fig. 4 is a plan-view of Fig. 1, the arrow in said figure indicating the direction of folding the interior stay of the device to the rear-member when collapsing the display-device into folded condition.

Similar letters of reference indicate corresponding parts throughout the different figures of the drawing.

Referring to the drawing, *a* represents the step-shaped rear-member of my improved display-device. To the edges of the step-shaped portions of the rear-member *a* are connected by means of hinge-flaps *a*¹ a plurality of individual transverse front-members *a*², each of which is of greater height than the height of the step-shaped portions of the rear-member *a*, so that the upper edge of the lowermost front-member *a*² overlaps the next adjacent or second member, the second member the third, and so on, as shown clearly in Fig. 3. Between the step-shaped rear-member *a* and the individual transverse front-members *a*² is interposed a step-shaped stay *d*, which is connected by a hinge-flap

*d*¹ with the rear-member *a* in such a manner that the inner edge of the stay is located in alinement with the center-line of the rear-member. The stay *d* is provided with steps *d*² which engage the lower edges of the front-member *a*² and serve for supporting the individual front-members at their lower edges when the stay *d* is placed in position normal to the rear and front members, as shown in Fig. 4. In this position of the stay *d* the rear and front members are flexed into convex or curved shape, the front-members being spaced apart from each other according to the width of the steps of the stay. The faces of the front-members are utilized for representing articles of merchandise in an effective manner, likewise the projecting end of the uppermost front-member. The display-device is preferably made of cardboard throughout, but it is obvious that other flexible or yieldable material can be used. The display-device is stored and shipped in the folded or collapsed condition shown in Fig. 3, and set up for use in the show-windows by bringing the stay from its position on one side of the rear-member into the forward position shown in Fig. 4, by which the front-members are spaced from each other and placed into convex position to the flexed rear-member, forming thereby an effective device for advertising purposes.

I have shown an embodiment of my invention, but changes may be made therein without departing from the spirit of my invention, as defined in the appended claims.

I claim:

1. A display-device, comprising a vertical rear-member, a vertical front-member, one of said members having its ends hingedly connected directly to the other member, and said members intermediate the hinged portions thereof being of the same length so as to be parallelly superposed when in collapse, and a vertical stay hinged to one of said members for flexing the members into extended position and convex shape.

2. A display-device, comprising a rear-member having its vertical edges arranged step-shaped, a plurality of front-members, each connected at opposite ends to the step-shaped portions on opposite edges, and a stay vertically arranged and hinged to the rear-member and adapted to be moved into position for flexing the members into convex shape.

3. A display-device, comprising a vertically-arranged step-shaped rear-member, a plurality of front-members each hinged to the opposite vertical edges of the step-shaped portions of the rear-member, the ends of the front-members being in direct connection with the rear-member, and a step-shaped stay hinged to the center-line of the rear-member and adapted to be moved intermediate the rear-member and the respective front-members, the steps of the stay

engaging the respective front-members, and said stay being vertically arranged, each front member extending over the lower edge of the adjacent front member thereabove. 15

In testimony that I claim the foregoing as my invention, I have signed my name in presence of two subscribing witnesses.

JULIEN STRANDERS.
